A. G. REDMOND

VALVE CONTROL FOR CARBURETORS

Original Filed March 6, 1917

UNITED STATES PATENT OFFICE.

ALBERT G. REDMOND, OF INDIANAPOLIS, INDIANA, ASSIGNOR TO MARVEL CARBURETOR COMPANY, OF FLINT, MICHIGAN, A CORPORATION OF INDIANA.

VALVE CONTROL FOR CARBURETORS.

Original application filed March 6, 1917, Serial No. 152,707. Divided and this application filed October 23, 1917. Serial No. 198,048.

To all whom it may concern:

Be it known that I, ALBERT G. REDMOND, a citizen of the United States, residing at Indianapolis, in the county of Marion and 5 State of Indiana, have invented certain new and useful Improvements in Valve Controls for Carburetors, of which the following is a specification, reference being had therein to the accompanying drawing.

10 This invention relates to certain new and useful improvements in carburetors, and more particularly to means for controlling the suction-controlled valve, and comprises a division of my application Serial No. 15 152,707, filed March 6, 1917. The object being to provide a construction of carburetor in which a high and low speed nozzle is employed for properly proportioning the mixture in accordance with the speed of the 20 motor to which the carburetor is attached.

Another object of the invention is to provide a carburetor which is exceedingly simple and cheap in construction, the parts being so arranged that they can be readily 25 reached for repairing the same, the high speed nozzle being protected by a suction-controlled valve normally held in closed position and adapted to be open by the increased suction when the motor to which the carburetor is attached exceeds a certain speed.

Other and further objects and advantages of the invention will be hereinafter set forth and the novel features thereof defined 35 by the appended claims.

In the drawings,

Figure 1 is a perspective view of my improved construction of carburetor.

Figure 2 is a transverse vertical section 40 through the same; and

Figure 3 is a detail elevation of a portion of the carburetor showing the rocker arm and spring for retarding the opening movement of the suction-controlled valve.

45 Like numerals of reference refer to like parts in the several figures of the drawings.

In the drawing 1 indicates the body of the carburetor which is provided with a mixing chamber 2 terminating in a tubular portion 3 which is provided with a flange 4 to facilitate its connection with the manifold of the motor, said tubular portion having a throttle valve 5 mounted therein carried by

a stem 6 which is provided at its outer end with a double crank 7 for controlling the 55 position of the throttle through the usual connection of the throttle control. The stem 6 carries a sleeve 7* which is provided with spaced lugs 8 adapted to cooperate with a stop lug 9 for positioning the throttle valve 60 in its open and closed position one of the lugs being provided with an adjustable screw 10 which enables the valve to be set so as to only partially close the tube.

The body of the carburetor is provided 65 with a laterally extending air passage 11 having a flange 12 adapted to be engaged by the flange 13 of an air pipe 14, said flanges being secured together by bolts 15 as clearly shown in Figure 1. 70

The air pipe 14 has an open end which is adapted to be connected to a suitable warm air supply and is provided with oppositely disposed air inlets 16 which are closed by a shutter 17 in the form of a split 75 collar having openings 18 adapted to register with the openings 16, said collar being mounted between spaced circumferential flanges 19 formed on the pipe 14, the ends of the shutter being secured together by a 80 bolt 20 so as to lock the shutter in its adjusted position. By this construction the size of the air inlets can be increased or diminished, and in use in mid summer weather the air inlets are entirely open and 85 in mid winter weather are entirely closed.

A horizontally disposed projection is formed in the body portion of the carburetor 90 forming a bottom for the mixing chamber and is provided with a vertically disposed bore 37 in which is mounted a Venturi tube 38, said horizontally disposed projection being arranged above a by-pass 39 which extends from the air inlet 11 as shown in 95 Figure 2.

The air tube 11 is closed at its inner end by a suction-controlled valve 54 carried by a valve stem 55 which has one of its ends extended into a box 56 formed integral with the body on one side as shown in Figs. 1, 2 and 3. The box is provided with an internally threaded opening 57 and in its bottom is mounted a hollow plug 58 having an externally threaded portion working in the threaded bore 57 for adjusting the position 100 of the hollow plug, said plug having a 105

milled head 59 which is engaged by a spring 60 for holding the plug in its adjusted position.

Arranged within the plug is a coil spring 5 61 which has its upper end arranged over a positioning pin 62 carried by a rock arm 63 secured on the outer end of the valve stem

55, said spring normally holding the arm in raised position so as to hold the suction-controlled valve closed so as to completely close the air inlet 11. The box 56 is provided with a removable cover 65 in order to allow the parts to be removed and taken apart for repairing.

15 In order to provide means for increasing the richness of the mixture for starting purposes I provide the air pipe 14 with a choker valve not shown carried by a valve stem 67 which extends out through the pipe and is 20 provided with an arm 68 forming means for connecting a rod or wire extending from the dash so as to close the valve. The valve is normally held open by a coil spring surrounding the stem having one of its ends 25 connected to the frame and the opposite end to a stop pin 69 formed on the pipe 14 which limits the movement of the arm so as to hold the choker valve in open position at all times. In starting the engine the operator operates the valve control on the dash so as to close the same which increases the 30 vacuum so as to draw into the cylinder a rich mixture from the mixing chamber.

From the above description it will be seen 35 that I have provided a carburetor with an air pipe having a shutter controlled air inlet by means of which air can be taken directly into the carburetor in connection with the suction-controlled valve normally held

closed. It will also be seen that the air inlet 40 of the carburetor is connected to the mixing chamber thereof by a by-pass in which is arranged a Venturi tube carrying a working nozzle for supplying fuel to the motor under ordinary conditions. 45

I claim:

1. A carburetor comprising a casing having a suction controlled valve mounted therein, a pivoted valve stem upon which said valve is mounted, extending through the 50 walls of said casing, an integral housing formed on said casing into which one end of said valve extends, an arm mounted on said stem within said housing, an adjustable support arranged within said housing and 55 a coiled spring carried by said adjustable support engaging said arm.

2. A carburetor comprising a casing having an integral housing, a valve stem extending through the walls of said casing 60 having one end arranged within said housing, a suction controlled valve carried by said valve stem, an arm fixed on said stem within said housing having a pin at its free end, said housing being provided with a threaded 65 opening, a hollow plug working in said threaded opening, said plug having a milled head and a spring arranged within said hollow plug having its free end arranged over the pin of said arm for retarding the movement thereof. 70

In testimony whereof I hereunto affix my signature in the presence of two witnesses.

ALBERT G. REDMOND.

Witnesses:

H. M. McCORMACK.
LUCIAN PAULEY.
